Attorney

UNITED STATES PATENT OFFICE.

HENRY W. CONARD, OF WYMORE, NEBRASKA.

PNEUMATIC GRIP FOR BICYCLES.

SPECIFICATION forming part of Letters Patent No. 587,388, dated August 3, 1897.

Application filed September 14, 1896. Serial No. 605,772. (No model.)

To all whom it may concern:

Be it known that I, HENRY W. CONARD, a citizen of the United States, residing at Wy-
more, in the county of Gage and State of Ne-
braska, have invented certain new and use-
ful Improvements in Pneumatic Grips for
Bicycles; and I do hereby declare the fol-
lowing to be a full, clear, and exact description
of the invention, such as will enable others
skilled in the art to which it appertains to
make and use the same.

My invention relates to an improvement in
bicycle-handles, my object being to provide
a pneumatic handle for bicycles whereby the
jarring incident to riding over rough surfaces
will not be imparted to the arms of the rider.

To this end the invention consists in the
various matters hereinafter described and
claimed.

20 In the accompanying drawings, which illus-
trate my invention, Figure 1 is a longitudinal
section of a handle embodying the present
improvement. Fig. 2 is a cross-section there-
of, and Fig. 3 is a detail.

25 Referring now more particularly to the
drawings, A represents a metallic core or base,
to which the parts of the device are applied.
This core may be a part of the usual handle-
bar or may be separately manufactured and
30 suitably attached to said handle-bar. The
handle B surrounding this core is attached
thereto. This handle comprises an outer
wall b, of rubber or other suitable flexible
35 fabric, and an inner tube b', which is also
preferably of rubber. The ends of the outer
wall b are attached to the ends of the inner
tube b', and in this way a bag is formed which
has a continuous air-chamber surrounding
40 the core A. The inner tube is cemented to
the core or attached thereto in any suitable
manner, and in order to strengthen the outer
wall and protect the same against puncture
a cover of canvas or other like material is
45 preferably provided about said outer wall.
The bag or pneumatic chamber B is thus at-
tached to the core by being slipped over the
same and cemented, and in order to protect
its outer end a plate or cap C is secured to
50 the outer end of the core, said plate or cap
extending over the end of the bag B.

The valve for inflating the bag is prefer-
ably located at the inner end of said bag and

is attached to the core or formed integrally
therewith. This valve comprises a base or
body portion D, through which is formed a 55
chamber d. A channel d' communicates with
this chamber at a suitable point to permit
said channel to communicate also with the
air-chamber formed in the bag. Preferably
a teat d² is formed upon the base, through 60
which teat the channel extends, the teat en-
tering the bag through the outer wall thereof.

One end of the chamber through the base
of the valve is closed by a removable plug d³,
and toward the other end of the chamber at 65
a point below the point at which the channel
enters said chamber the walls of the chamber
are narrowed in order to form a shoulder or
valve-seat d⁴, upon which rests a spherical or
other suitably-shaped valve d⁵, said valve 70
being held in place by the coil-spring d⁶, bear-
ing at one end upon the plug in the end of
the chamber. The end of the chamber be-
low the valve-seat is also closed by the plug
d⁷, this end of the chamber being so con- 75
structed that an air-pump can be attached
thereto.

It is thought that the operation of the pres-
ent device is apparent. The plug d⁷ closes
the entrance of the chamber against dust or 80
other objectionable matter and protects the
valve from being accidentally released from
its seat. The valve being located in the cham-
ber as described it can be readily removed for
cleaning or repair and the chamber extending 85
through the base can be easily cleaned.

Having thus described my invention, what
I claim as new, and desire to secure by Letters
Patent, is—

1. The combination with the body portion 90
of the handle, of a flexible bag about the
same, a base at one end having a passage ex-
tending transversely of the length of the
handle, and a channel leading therefrom to the
interior of the bag, a valve in said chamber, 95
a spring arranged within the chamber acting
on said valve, and a plug at the opposite end
of said base, substantially as described.

2. The combination with the core, of a han-
dle surrounding the same and comprising an 100
outer wall of flexible material, and an inner
tube also of flexible material, said inner tube
being attached to the core, a cap secured in
the outer end of the core and extending over

the end of the inflatable portion, a base at the opposite end of the core having a passage at right angles to the length of the handle, and a channel communicating therewith and with the interior of the inflatable portion, a plug in one end of said chamber, and a valve in the other with an interposed spring, all substantially as herein specified.

In testimony whereof I have signed this specification in the presence of two subscr- 10
ing witnesses.

HENRY W. CONARD.

Witnesses:

FRANK L. WICKS,
JOHN GAGNON.
